FRANCIS B. ALLDREDGE, OF DES MOINES, IOWA, ASSIGNOR OF ONE-FIFTH TO BAIR,
FREEMAN & SINCLAIR, OF DES MOINES, IOWA, A COPARTNERSHIP COMPOSED OF
WILLIAM P. BAIR, WILL FREEMAN, AND EARL M. SINCLAIR

OPEN FLOW BAILER VALVE

Application filed October 10, 1928. Serial No. 311,499.

My present invention has to do with a valve used for bailers of the kind employed for instance in taking liquids and other matter out of oil wells and the like.

5 It is the purpose of my invention to provide a valve adapted for use in such a bailer, so constructed and arranged and mounted in the bailer as to afford a maximum opening for the passage of fluid and other material past the valve upwardly and downwardly.

10 With these and other objects in view, my invention consists in the combination, arrangement and construction of the various parts of my valve, whereby the objects contemplated are attained as hereinafter more fully set forth, pointed out in my claims, and illustrated in the accompanying drawings, in which:

15 Figure 1 is a vertical, sectional view through the lower portion of a bailer equipped with a valve embodying my invention, the upper part of the bailer and the lower part of the valve stem being broken away.

20 Figure 2 is a vertical, sectional view taken at right angles to the view shown in Figure 1; and

25 Figure 3 is a view similar to that shown in Figure 1 illustrating the valve in its open position.

30 It is a common practice in the oil fields to use for removing liquids and some other matter from oil wells, bailers which have in their lower ends valves having downwardly projecting stems so arranged that when the bailer is dropped the stem engages some obstruction and raises the valve to permit liquid and other matter to flow upwardly through the bottom of the bailer into the 35 bailer past the valve.

40 These valves are so arranged as to automatically close when the bailer is raised until the valve stem clears such obstruction.

45 The valves heretofore employed have been subject to the objection that their construction was such as to permit the employment of a relatively small opening at the valve seat and to allow only a limited opening for the 50 passage of fluid and the like when the valves were open.

I have in my present valve structure provided one which eliminates these objections and affords a larger maximum opening around the valve and a much freer passage past the valve when the valve is open.

55 In the accompanying drawings, I have shown my valve assembled in connection with a bailer indicated in the accompanying drawings by the reference numeral 10. The bailer 10 comprises a tubular member open at its lower end. Projected into the lower end of the bailer 10 is a valve casing 12, which has at its upper portion an exterior, annular 60 rabbet 14 to receive the lower end of the bailer 10.

65 The valve casing 12 projects downwardly substantially below the lower end of the bailer 10.

70 The upper end of the casing 12 forms a valve seat 16 within the lower end of the bailer spaced inwardly from the wall thereof and spaced above the lower end of the bailer.

75 My improved valve 18 comprises a member having generally the form of a hemisphere with the flat side normally up as illustrated in Figure 1. Formed or arranged on what is normally the flat upper surface of the valve 18 is what I shall for convenience call a valve mounting element 19. I shall describe this mounting element as though the valve were in its normal closed position in an 80 upright bail.

85 The mounting element 19 has the form of a body, the thickest portion of which is in line with the vertical axis of the valve. The upper surface of the element 19 is inclined from its upper part downwardly and practically to the edge of the valve 18 for a little more than a half of the circumference of the upper part of the valve.

90 Extending from the upper central portion of the element 19 is an engaging member 19a, the upper surface of which is rounded and inclined from its upper part downwardly and laterally as shown in the drawings.

95 There is thus formed between the lower projecting part of the member 19a and the valve 18 a substantially horizontal passage 20, which registers and communicates with a transverse L-shaped slot 22 in the central and upper portion of the element 19. The 100

slot 22 extends horizontally from the passage 20 and then upwardly as at 22a.

The valve is mounted in the casing 12. The upper end of the casing 12 has on opposite sides upwardly projecting ears 24 illustrated for instance in Figure 3, which are slightly less thick than the general body of the casing 12, as illustrated for instance in Figure 2.

16 A pin 26 is received in suitable holes 28 in the ears 24 and projected through the slot 22 as illustrated in all of the figures.

15 In the under side of the valve 18 is a transverse slot 30 extending more than half way horizontally across the valve as illustrated.

16 There is provided a valve stem 32, the upper end of which is received in the slot 30 and is pivotally supported on the valve by means of a pin 34 extended horizontally through the lower part of the valve and through the upper end of the stem 32 in such manner as to permit free pivotal movement of the stem on a horizontal axis.

23 The pin 34 is parallel with the pin 26 but is slightly off the vertical axis of the valve as shown in Figure 1 on the side of the valve opposite the passage 20—that is to say to the left of the passage 20 as the parts are shown in Figure 1.

35 The lower part of the stem is widened as at 32a to slide and fit snugly in the lower part of the casing 12. At its lower end the portion 32a has the opposite shoulders 32b, so arranged as to serve as a stop when the valve is actuated in the manner now to be described.

40 Assume that the parts are in their normal positions shown in Figures 1 and 2, then the practical operation of the valve may be described as follows:

45 If the bailer 10 is lowered into an oil hole until the lower portion 32a of the stem 32 meets any obstruction 36, it will be seen that the stem will be forced upwardly because of the offset arrangement of the pin 34 with relation to the pin 26, and the valve will be tilted from its position shown in Figure 1 to its position shown in Figure 3.

50 The parts are so arranged that when the valve is tilted to the position shown in Figure 3, the shoulders 32b will engage the lower end of the valve casing 12 and prevent any further upward movement or further tilting of the valve 12.

55 When the valve is thus tilted instead of being raised directly upright, it is seen that a comparatively large passage A is afforded alongside the valve. This facilitates the quick tilting and emptying of the bailer.

60 When the bailer is drawn upwardly, the weight of the stem and the valve is such that the valve will automatically drop to seated position.

65 After the bailer has been withdrawn from the hole, it may be emptied by lowering it

until the valve opening operation again occurs.

The casing 12 is mounted in the lower end of the bailer 10 in any suitable way to permit the removal of the casing 12 for purposes of valve repair or replacement.

75 With a valve and valve mounting of this kind, the total area of the opening at the valve seat is the maximum that would be possible and the passage A is large enough so that clogging of the bailer may be almost entirely eliminated. This is a very important feature because bailers of this kind are hard to clean out when the valve opening is clogged.

80 There are a number of advantages also in the details of the structure of the present device.

85 It will be noted that when the valve is in normal seated position, as shown for instance in Figure 1, it can not tilt upwardly to the right because of the engagement of the stem 32 with the wall 30a of the slot 30.

90 The construction is such that the slot 30 is covered at all times so that it is not likely to be clogged by material passing downwardly from the bailer.

95 The slot 22 is also covered and the material on both sides of the slot 22 is preferably beveled as indicated for instance at 38 in Figure 2 to prevent the catching of any pebbles or other material that might lodge in the slot.

100 The same is true of the material above and below the passage 20.

105 The bailer may be let down through many feet of liquid, and it is obvious that the liquid itself may force the valve 18 off its seat, so that the bailer can slide through the liquid without difficulty. When the bailer reaches the bottom of the hole, it is sometimes churned up and down, in order to cause it to take in, not only liquid, but dirt and rocks. In order to permit this action, the valve has the loose pivotal and sliding connection with the pin 26, which permits the valve to raise and also to tilt and slide on the pin for moving to its open position shown in Figure 3.

110 The construction and arrangement of the parts of my improved valve and valve mounting may be varied somewhat as to details without departing from the real spirit and purpose of my invention, and it is my intention to cover by my claims any modified forms of structure or use of mechanical equivalents, which may be reasonably included within 115 their scope.

120 I claim as my invention:

1. In a structure of the class described, the combination of a bailer member having an open lower end, with a valve seat in such 125 lower end, a movable valve for cooperating with said seat, a pivoted stem projecting from the valve below the bailer, and means for operatively connecting the valve with the bailer to cause the valve to tilt and slide upwardly 130

away from the seat when the bailer is lowered to cause the stem to engage an obstruction.

2. In a structure of the class described, the combination of a bailer member having an open lower end, with a valve seat in such lower end, a movable valve having a seating surface in the form of a portion of a sphere, for cooperating with said seat from above, a 10 slideable, pivotal mounting for the valve above its central part, and a down-hanging stem for actuating the valve for opening movement pivotally and slidably on such mounting.

15. 3. In a structure of the class described, the combination of a bailer member having an open lower end, with a valve seat in such lower end, a movable valve for cooperating with said seat, a stem pivoted to the under side of the valve and projecting below the casing, and means for loosely slidably mounting the valve above its center, to permit it to be actuated by the stem for tilting it.

4. In a structure of the class described, the combination of a bailer member having an open lower end, with a valve seat in such lower end, a movable valve for cooperating with said seat, a stem pivoted to the under side of the valve and projecting below the casing, and means for loosely slidably mounting the valve above its center, to permit it to be actuated by the stem for tilting it, so that one side swings upwardly and the opposite side downwardly.

35. 5. In a structure of the class described, the combination of a bailer member having an open lower end, with a valve seat in such lower end, a movable valve for cooperating with said seat, a stem pivoted to the under side of the valve, and guide means on the bailer member for mounting the valve for limited vertical and for tilting movement.

6. In a structure of the class described, the combination of a bailer member having an open lower end, with a valve seat in such lower end, a movable valve for cooperating with said seat, a stem pivoted to the under side of the valve, and means for mounting the valve for limited vertical and for tilting movement on an axis parallel with that of the stem pivot.

7. In a structure of the class described, the combination of a bailer member having an open lower end, with a valve seat in such lower end, a movable valve for cooperating with said seat, a stem pivoted to the under side of the valve, and means for mounting the valve for limited vertical and for tilting movement on an axis parallel with that of the stem pivot, one of said axes being off the normal vertical axis of the valve.

8. In a structure of the class described, the combination of a bailer member having an open lower end, with a valve seat in such lower end, a movable valve for cooperating

with said seat, a stem pivoted to the under side of the valve, and means for mounting the valve for limited vertical and for tilting movement on a horizontal axis parallel with that of the stem pivot.

9. In a structure of the class described, the combination of a bailer member having an open lower end, with a valve seat in such lower end, a movable valve for cooperating with said seat, a stem pivoted to the under side of the valve, and guide means on the bailer member for mounting the valve for limited vertical and for tilting movement on a horizontal axis.

10. In a structure of the class described, the combination of a bailer member having an open lower end with an interior annular valve seat, with a valve for cooperating with such seat, having its seating face in the shape of a portion of the surface of a sphere, guide means on the bailer member for mounting the valve to permit it to be tilted on a horizontal axis above its seating plane.

11. In a structure of the class described, the combination of a bailer member having an open lower end with an interior annular valve seat, with a valve for cooperating with such seat, having its seating face in the shape of a portion of the surface of a sphere, guide means on the bailer member for mounting the valve to permit it to be tilted on a horizontal axis above its seating plane, and a stem pivoted to the lower part of the valve to hang downwardly.

12. In a structure of the class described, the combination of a bailer member having an open lower end with an interior annular valve seat, with a valve for cooperating with such seat by seating from above, having its seating face in the shape of a portion of the surface of a sphere, means on the bailer member for mounting the valve to permit it to be tilted on a horizontal axis above its seating plane, and a stem pivoted to the lower part of the valve on a parallel axis to hang downwardly.

13. In a structure of the class described, the combination of a bailer member having an open lower end with an interior annular valve seat, with a valve for cooperating with such seat, having its seating face in the shape of a portion of the surface of a sphere, means on the bailer member for mounting the valve to permit it to be tilted on a horizontal axis above its seating plane, said valve having in its under surface a slot extending horizontally from its periphery past its vertical center (when seated) and a stem pivoted in said slot.

14. In a structure of the class described, the combination of a bailer member having an open lower end with an interior annular valve seat, with a valve for cooperating with such seat, having its seating face in the shape of a portion of the surface of a sphere, means

on the bailer member for loosely mounting the valve to permit it to be tilted on a horizontal axis above its seating plane, said valve having in its under surface a slot extending horizontally from its periphery past its vertical center (when seated) and a stem pivoted in said slot, on an axis parallel with said first axis.

15. In a structure of the class described, the combination of a bailer member having an open lower end with an interior annular valve seat, with a valve for cooperating with such seat, having its seating face in the shape of a portion of the surface of a sphere, means on the bailer member for mounting the valve to permit it to be slid and to be tilted on a horizontal axis above its seating plane, and a pivoted stem for causing the tilting movement of the valve, said stem coacting with the bailer member to limit the movement of the valve in opening.

16. In a structure of the class described, the combination of a bailer member having an open lower end with an interior annular valve seat, with a valve for cooperating with such seat, having its seating face in the shape of a portion of the surface of a sphere, means on the bailer member for mounting the valve to permit it to be bodily raised and to be rocked on a horizontal axis centrally above its seating plane, and means for limiting the rocking movement of the valve, said last means serving to constrain the valve toward seated position.

17. In a structure of the class described, the combination of a bailer member having an open lower end with an interior annular valve seat, with a valve for cooperating with such seat by seating from above, having its seating face in the shape of a portion of the surface of a sphere, means on the bailer member for mounting the valve above its seat to permit it to be bodily raised and also rocked on a horizontal axis centrally above the seat.

18. In a structure of the class described, the combination of a bailer member having an open lower end with an interior annular valve seat, with a valve for cooperating with such seat, means on the bailer member for mounting the valve for limited bodily slideable movement.

19. In a structure of the class described, the combination of a bailer member having an open lower end with an interior annular valve seat, with a valve for cooperating with such seat, means on the bailer member for mounting the valve for limited bodily slideable movement and for pivotal movement.

20. In a structure of the class described, the combination of a bailer member having an open lower end with an interior annular valve seat, with a valve for cooperating with such seat, means on the bailer member for mounting the valve for limited bodily slideable movement and for pivotal movement,

and means for actuating the valve for opening movement, the parts being so arranged that when the valve is so operated it is tilted and also slid laterally toward the wall of the bailer member.

21. In a structure of the class described, the combination of a bailer member having an open lower end with an interior valve seat with a valve for cooperating with such seat, means on the bailer member for mounting the valve for limited vertical and bodily sliding movement and for pivotal movement, and means for actuating the valve for opening movement, the parts being so arranged that when the valve is operated it is lifted, tilted and also slid laterally toward the wall of the bailer member.

Des Moines, Iowa, September 13, 1928.
